UNITED STATES PATENT OFFICE.

GEORGE J. WEBER, OF KANSAS CITY, MISSOURI.

ROTARY EXPLOSIVE-ENGINE.

No. 873,916.

Specification of Letters Patent.

Patented Dec. 17, 1907.

Application filed December 2, 1904. Serial No. 235,215.

To all whom it may concern:

Be it known that I, GEORGE J. WEBER, a citizen of the United States, residing at Kansas City, in the county of Jackson and State 5 of Missouri, have invented certain new and useful Improvements in Rotary Explosive-Engines; of which the following is a specification.

My invention relates to improvements in 10 explosive engines.

The object of my invention is to provide an explosive engine having a piston and an explosion chamber, with means for admitting a charge into the explosion chamber, means for 15 igniting the charge in the explosion chamber, means for preventing the expansion of the ignited charge until it has attained its maximum pressure, and means for then permitting it to expand against the piston. By 20 this mechanism the full expansive force of the ignited charge suddenly impinges against the piston, instead of having the force reduced by movement of the piston before the highest attainable pressure of the charge has been 25 obtained.

My invention is applicable particularly to explosive engines of the type having a rotary piston, that is, engines of the "turbine" type.

30 My invention provides further, a construction in which a rotary piston is provided with a plurality of blades to receive the force of the charge combined with means for igniting the charge and preventing the expansion of the ignited charge until it has attained its greatest explosive force, and then providing means for permitting the ignited charge to expand against the blades of the piston.

40 My invention provides further, a construction in which one or more of the constituents of the charge is first compressed, then ignited, and prevented from expanding until the maximum expansive force is attained, and then permitted to expand in contact with the piston.

45 My invention provides further a construction in which one or more of the constituents of the charge is highly compressed, means for then commingling therewith another constituent of the charge, the admixture of which causes ignition of the combined mixture due to the heat evolved by the compression of part of the charge, and means by 50 which the ignited charge suddenly impinges against the piston.

My invention provides further, the compressing of the charge to a degree in which sufficient heat is developed to cause ignition of the charge, retaining the ignited charge 60 from expansion until the maximum explosive pressure is attained and then permitting the ignited charge to expand in contact with the piston.

My invention provides certain other features of novelty hereinafter described and claimed.

In the accompanying drawings illustrative of my invention—Fig. 1 is a vertical section view taken on the dotted line *c—d* of 70 Fig. 2, and showing the inlet of the explosion chamber open and the outlet thereof closed. Fig. 2 is a vertical sectional view taken on the dotted line *a—b* of Fig. 1, some of the parts being shown in elevation. Fig. 3 is a 75 front elevation view of some of the parts controlling the entrance and exit of the charge into and from the explosion chamber. In this view the parts are shown in dotted lines in the positions occupied by them when the valves controlling the ports in the explosion chamber are in the positions shown in Fig. 1. In solid lines in this view the parts are shown in the positions occupied by them when the valves controlling the said ports have moved 80 so as to cover the inlet port. In this view is also shown a modified means for retracting the valve controlling the outlet port of the explosion chamber. Fig. 4 is a front elevation view of the engine, showing the parts in the 85 positions occupied by them when the valves controlling the ports of the explosion chamber are as shown in Fig. 1. The compressing pump mechanism is shown partly in vertical section in this view. Fig. 5 is a top view of 90 the engine with a portion of the parts in horizontal section. Fig. 6 is a top view of part of the mechanism connected with the valve located in the supplemental chamber. Fig. 95 7 is a side elevation view of the crank affixed to the operating shaft of the valve in the supplemental chamber. Fig. 8 is a similar view of a bell crank lever rotatably mounted on the said operating shaft. Fig. 9 is a similar 100 view of the wiper mounted on the said shaft. Fig. 10 is a vertical sectional view of a portion of the explosion chamber provided with means for injecting fuel therein in addition to the inlet port. Fig. 11 is a front elevation view of a modified form of cam.

105 Similar characters of reference indicate similar parts.

110

In the drawings I have illustrated my invention as applied to a rotary engine of the "turbine" type.

1 indicates a cylindrical piston provided 5 with a plurality of peripheral pockets 2 and mounted upon and rotatable with a rotatable shaft 3 mounted in suitable bearings in the casing 4 which encircles the piston 1 and is provided with a hollow water space 5 embracing the part of the casing forming the cylinder 6 in which the piston is mounted. 10 Connected by an outlet port 7 with the cylinder 6 is the explosion chamber 8 provided with an inlet port 9 connecting the explosion chamber with the supplemental chamber 10 in which is oscillatively mounted a rock valve 11 adapted to open and close the port 9. In the explosion chamber is oscillatively mounted a rock valve 12 adapted to 15 cover and uncover the ports 7 and 9. The face of the valve 12 is sufficiently wide to cover both said ports simultaneously. Each of the valves 11 and 12 is provided with an annular groove 13 in which the charge is 20 received. Between the ends of said groove is the valve face 14 comprising a radial extension the outer surface of which is fitted to the interior of the chamber in which the valve is located. Each valve is hollow and 25 provided with a horizontal tubular extension 15 which extends through the casing and has mounted on it a cap 16 provided with a tubular outlet 17. Extending through each cap 16, extension 15, and into the hollow 30 space in the valve, is a horizontal tube 18 through which a cooling fluid, as water, is injected into the valve. The cooling fluid then passes out the valve through the extension 15, cap 16, and tubular outlet 17. En- 35 circling each extension stem 15 is a spring 19, the outer end of which bears against the cap 16 and the inner end of which bears against the casing of the engine. The tension of each of the springs 19 is such that the valves 40 11 and 12 are drawn tightly against the inner wall of the casing, thus preventing leakage of the gas around the stems 15.

Rocking or reciprocating motion is imparted to the valves 11 and 12 in the following manner: A horizontal rock shaft 20 extending through the casing is connected with the forward end of the valve 12 and rocking therewith. The outer end of said rock shaft has mounted thereon and rocking therewith 45 a bell crank lever 21, to one arm of which is pivotally connected a connecting bar 22, the lower end of which is pivotally connected with the upper end of a bar 23, reciprocatively mounted in a hole provided in the 50 guide 24 extending outwardly from the forward side of the casing. Upon the lower end of the bar 23 is mounted a roller 25 which forms an antifriction bearing upon the cam 26 which is mounted on and rotatable with the 55 shaft 3. To the arm of the bell crank lever 21

to which is pivoted the connecting bar 22 is connected one end of a spring 27 the other end of which is secured to a pin 28 extending forwardly from the casing. The tension of the spring 27 is such that the valve 12 will be 70 retracted by it after the valve has been rotated to cover the port 7, by means of the cam 26 and mechanism just described. It being desirable to regulate the degree to which the port 7 is uncovered by the valve 75 12 to obtain the greatest efficiency in the expansion of the ignited charge in the explosion chamber, I provide on the bell crank lever 21 an arm 29 which is adapted to strike a horizontal screw 30 mounted in a screw threaded hole in a projection 31 on the forward side of the casing. The projection 31 is disposed at the right of the arm 29, as viewed in Fig. 4, so that the rocking of the arm 29 in that direction is 80 checked by the screw 30. By adjusting the screw the stroke in one direction of the valve 12 over the port 7 is regulated. A lock nut 32 may be mounted on the screw 30 so as to bear against the projection 31. Extending 85 forwardly through the casing is another rock shaft 33, secured to and oscillatable with the valve 11. Upon the forward part of the rock shaft 33 outside the casing is pivotally mounted a bell crank lever 34, one arm of 90 which is provided with a forwardly extending pin 35, to which is pivotally connected one end of a rod 36, the other end of which is connected pivotally with one of the arms of the bell crank lever 21. On the other arm 95 of the bell crank lever 34 is pivoted one end of a pawl 37, the other end of which is adapted to engage a tooth 38 provided on a lever 39 which is mounted on and keyed to the rock shaft 33. The other end of the lever 39 100 has pivoted to it the upper end of a rod 40 the lower end of which is pivoted to a piston 41 reciprocatively mounted in a cylinder 42, secured to the forward side of the casing. The piston 41 and cylinder 42 serve as a 105 dash pot to slow the movement downward of the piston, the piston 41 serving to close the valve 11 after it has been opened by reason of the rocking of the bell crank lever 21 and parts connected therewith and already described.

When the engine is running slowly the cam 26, through the connecting mechanism described, rocks the bell crank lever 34 forward and backward with each rotation of the 110 piston 1, and with each movement to the right of the bell crank lever 34, as viewed in Fig. 4, the pawl 37 is caused to engage the tooth 38 and carry with it the lever 39, thus rocking the valve 11 and uncovering the port 9, permits the passage therethrough from the supplemental chamber 10, of the charge, which then enters the explosion chamber 8. After the charge has entered the chamber 8, 115 it is exploded, both valves being then closed, 120 125 130

after which the valve 12 is opened, and the charge passes through the port 7 into the cylinder 6, where it impinges against the blades on the piston and causes rotation of the piston 1. After each explosion and escape into the cylinder 6 of the charge, the valve 12 is retracted by the cam 26 and parts connected therewith, and caused to cover the port 7 at which time the valve 11 is rocked so as to uncover the port 9 so as to receive a fresh charge into the explosion chamber 8.

When the speed of rotation of the piston 1 has reached the proper limit, it is desirable to hold the valve 11 closed so as to prevent the passage into the explosion chamber 8 of any charge while the proper speed of rotation of the piston is retained. To accomplish this I mount on the rock shaft 33 a lever 43, disposed outside the lever 39 and provided with an inclined upper side adapted to be brought in contact with a pin 44 on the pawl 37 and raise the pawl so that it will miss the tooth 38 on the lever 39, and thus miss rocking the valve 11 in a direction in which the port 9 would be opened. When the speed is low the lever 43 is in a position such that the inclined upper side will not make contact with the pin 44 on the pawl 37. When the speed of the piston rises to the proper limit any suitable governing mechanism, not shown, may be caused to move the arm 45 pivoted to one end of the lever 43 in a direction such that the inclined face thereof will engage the pin 44 and lift the pawl from engagement with the tooth 38. By this mechanism the charge admitted may be varied in volume, the amount of uncovering of the port 9 by the valve 11 depending upon the time that the pawl 37 is raised by the lever 43, which time depends upon the position of the lever 43. Any desirable mechanism for regulating the movement of the arm 45 may be employed.

Compression of the charge is obtained as follows:—Mounted on the shaft 3 and rotatable therewith is an eccentric collar 46, which is embraced by the upper end of a cam rod 47, the lower end of which is pivoted to the upper end of a bar 48, the lower end of which is secured to the upper side of a vertically reciprocable piston 49, mounted in a cylinder 50 secured to the forward side of the casing 4, and closed at the bottom and open at the top. Connected to the lower part of the cylinder 50, are two check valve casings 51 and 52, each of which is provided with a plug 53, removably fitted in the casing above a valve opening. The said valve openings are controlled respectively by the valves 54 and 54' which are vertically movable in the plugs 53, one in each of said plugs. As the piston 49 is raised air is drawn through the valve casing 51 past the valve 54 and into the cylinder, the valve 54 being then closed. As the piston 49 descends the air is forced past the

valve 54' through the valve casing 52 and through a conducting pipe 56 into a storing chamber 57, the valve 54' being then closed. A pipe 58 is connected at one end with the chamber 57 and at the other end with one end of a valve casing 59 the other end being connected to the pipe 60 extending through the casing 4 and discharging into the supplemental chamber 10. The valve casing 59 is provided with a removable plug 61 in which is mounted a vertically movable valve 62 adapted to close a valve opening 63 in the valve casing 59.

When the valve 11 is in the position shown in Fig. 1, the pressure of the fluid in the chamber 57 causes the check valve 62 to rise and permits the compressed fluid to enter the supplemental chamber 10 from which it passes through the port 9 into the explosion chamber 8. The valves 11 and 12 are then moved so as to close the port 9, the valve 12 still covering the port 7. When the fluid admitted to the explosion chamber is air alone, fuel, such as oil, may then be admitted into the explosion chamber through a pipe shown in Fig. 10, and caused to mingle with the highly compressed air. The heat of the compressed air then ignites the mixture at which time the pressure rises to the maximum, the ignited charge being prevented from expanding immediately. The valve 12 is then rocked by means of the spring 27, bell crank lever 21 and shaft 20 so as to uncover the port 7. The distance moved by the valve in this direction is regulated by the screw 30 coming into contact with the arm 29 on the lever 21. By adjusting the screw 30, when the engine is running, the throw of the valve may be regulated in a manner to secure the greatest efficiency from the fuel used. The port 7 is preferably bifurcated at its outer end, the branch 64 having its exit orifice so disposed that the two branches of the port may simultaneously impinge against two blades on the piston. By this arrangement of the valve 12 and the port 7 the expansive power of the charge is fully appropriated to drive the piston.

Instead of igniting the charge by the liberation of heat due to compression of the air, the charge may be ignited by any other means, as, for instance, by a jump spark. For this purpose a wire 65 is connected to the outer end of an electrode 66 located in and protected by the insulation 67 from the metallic plug 68 which is mounted in a screw threaded opening extending through the casing into the explosion chamber 8. The inner end of the plug is provided with an electrode 69 disposed adjacent to but not touching the inner end of the electrode 66. A wire 70 has one end connected with a U-shaped metallic spring 71 mounted upon but insulated by insulation 72 from a projection 73 extending forwardly from the front of the casing 4.

Upon the free end of the spring 71 is mounted in a screw threaded hole in the spring, a screw 74 which may be secured by a lock nut 75 mounted on the screw and adapted to bear against the spring 71. Upon the bar 22 is mounted movably therewith a contact plate 76 which is adapted to strike the upper end of the screw 74 when the rod 22 descends and after the valve 12 is closed over the two ports 7 and 9. By adjusting the position of the screw 74 upon the spring 71 while the engine is running, the proper time for igniting the charge is obtained.

Any suitable source of electric current may be employed for obtaining the jump spark between the electrodes 66 and 69, the two wires 65 and 70 being interposed and forming part of the electric circuit in which the current is passed. From the contact plate 76 the circuit is completed through the engine to the electrode 69 by means of the rod or bar 22, bell crank lever 21, rock shaft 20, casing 4 and plug 68. If desired, a portion only of the fuel may be mixed with the air before the same is compressed by injecting it into the inlet opening in the valve casing 51 through a pipe 77 connected with some suitable fuel supply. If desired, all of the fuel may be drawn into the chamber 57 from this source and the pipe 78 leading to the explosion chamber, and shown in Fig. 10, dispensed with.

To prevent leakage from the front of the casing 4 around the rock shafts 20 and 33, each of said rock shafts is provided inside the casing with a flange 79 which is forced by the force of the gas pressure tightly against the inner wall of the casing forming the supplemental chamber and the explosion chamber. Leakage from the other ends of said chambers is prevented as already described.

As shown in Fig. 3, other means than the spring 27 may be employed to retract the valve 12 to uncover the port 7. Pivoted to the same place on the lever 21, to which the spring 27 is secured when used, is the upper end of a rod 80, the lower end of which is pivotally connected to the upper end of a piston 81, reciprocatively mounted in a cylinder 82, secured to the forward side of the casing 4. The weight of the piston 81 serves to retract the valve 12 through the intermediacy of the connecting mechanism described. An outlet for air may be provided, as indicated, by 83 in the wall of the cylinder 82, below the piston 81. A similar air outlet may be provided in the cylinder 42.

When the valve 12 is in the position shown in Fig. 1, the roller 25 is on the arcuate portion of the cam 26, as shown in Fig. 4, and at this time the charge is being admitted into the explosion chamber 8. As soon as the cam so moves that the wheel or roller 25 passes off this portion of the cam, the cam 65 moving to the right, as viewed in Fig. 4, the

roller 25 will drop into a recessed portion of the cam indicated by 84. This recessed portion 84 is so shaped that the roller 25 will be held from descending further for a brief period at which time the valve 12 will have moved to the left, as viewed in Fig. 1, and will cover both ports 7 and 9. At this time the contact plate 76 will strike the screw 74 in the spring 71, thus completing the circuit through the engine, and permitting the jump spark to pass between the electrodes 66 and 69, and ignite the charge, which, at this time is isolated in the explosion chamber. The charge being thus isolated and held from expanding when ignited will attain at once its maximum pressure. The cam 26 continuing to move forward, the roller 25 will drop suddenly off the recessed portion 84 of the cam, and the spring 27 will still further retract the valve 12 until the arm 29 strikes the screw 30, at which time the valve 12 will have uncovered the port 7 and the ignited charge will issue through the port 7 at its greatest pressure. The valve 11, in addition to regulating the feeding of charges to the explosion chamber, also serves as a further means for preventing the ignited charge from igniting the gas in the supplemental chamber 10. As an additional safeguard the check valve 62 is provided, so that in the event that the ignited charge did pass through the inlet 9, the ignited gas in the supplemental chamber could not ignite the compressed mixture in the storing chamber 57.

In Fig. 11 I have shown a modified form of cam in which two arcuate surfaces are used instead of one to raise the roller 25. Two recessed portions 84 are employed in the cam, which is indicated by 85. With a two point cam, such as this one, the valve 12 is rocked twice during each rotation of the piston 1. The valve 11 may thus also be rocked twice during each rotation of the piston, thus permitting two charges to enter the explosion chamber 8 during one revolution of the piston. The power of the engine may thus be increased over what is acquired by using the form of cam hereinbefore described.

As noted in Fig. 1, the cylinder 6 is provided near the bottom with an outlet opening 86 for the escape of the products of combustion.

My invention may be modified in different ways without departing from its spirit.

Having thus described my invention, what I claim and desire to secure by Letters Patent is:—

1. In explosive engines, the combination with the cylinder, of an explosion chamber provided with an inlet port for admitting the charge and having an outlet port connecting the explosion chamber with the cylinder, a rocking valve controlling both ports, means for moving the valve so as to close the inlet port after the charge is admitted and so as to

open the outlet port, and means for igniting the charge after the inlet port is closed and prior to the opening of the outlet port.

2. In explosive engines, the combination 5 with the cylinder, of an explosion chamber provided with an inlet for admitting the charge and having an outlet port connecting the explosion chamber with the cylinder, a valve controlling both ports, means for rocking 10 the said valve, and means independent of the running of the engine for regulating the degree that the outlet port is uncovered.

3. In explosive engines, the combination 15 with the cylinder, of an explosion chamber provided with an inlet for admitting the charge and having an outlet port connecting the explosion chamber with the cylinder, a rocking valve mounted in the explosion chamber and provided with a face broad 20 enough to simultaneously cover both ports, means for rocking the said valve over the said ports, and means for igniting the charge when the ports are both covered.

4. In explosive engines, the combination 25 with the cylinder, of an explosion chamber provided with an inlet for admitting the charge and provided with an outlet through which the full charge in the chamber escapes after each explosion and connecting 30 the explosion chamber with the cylinder, a rocking valve for opening and closing the said outlet, means for igniting the charge when the valve is in a closed position, and means for rocking said valve independently 35 of the pressure of the charge in the explosion chamber.

5. In explosive engines, the combination 40 with the cylinder, of an explosion chamber provided with an outlet connecting the said chamber with the cylinder, means for exploding a charge admitted to the explosion chamber, a supplemental chamber provided 45 with an outlet connecting the said supplemental chamber with the explosion chamber and provided with an inlet for admitting the charge into the supplemental chamber, a valve controlling the said inlet, a rocking valve controlling the outlet of the supplemental chamber, and means by which the 50 inlet and outlet to the explosion chamber may be held closed during an explosion.

6. In explosive engines, the combination 55 with the cylinder, of an explosion chamber provided with an outlet connecting the said chamber with the cylinder, means for exploding the charge in the combustion chamber, a rocking valve controlling the said outlet, a supplemental chamber provided with an outlet connecting with the explosion 60 chamber, a valve controlling this outlet, means for admitting a charge into the supplemental chamber, means for actuating both of said valves so as to simultaneously retain closed the outlets controlled by them, 65 and means by which the valve in the explo-

sion chamber may be actuated independently of the other valve.

7. In explosive engines, the combination 70 with the cylinder, of an explosion chamber provided with an outlet connecting the said chamber with the cylinder, a piston movably mounted in the cylinder, a conductor for admitting the charge to the explosion chamber, a valve actuated independently of the pressure in the explosion chamber controlling 75 the passage of the charge through the said conductor, a valve controlling the outlet of the explosion chamber, means actuated by the movement of the piston for moving the said valves in one direction, and means 80 for moving independently of each other the said valves in the opposite direction.

8. In explosive engines, the combination 85 with the cylinder, of an explosion chamber provided with an outlet connecting the said chamber with the cylinder, a piston movably mounted in the cylinder, a supplemental chamber having an inlet for admitting the charge therein and having an outlet connecting with the explosion chamber, two oscillatory valves, one controlling the outlet of the combustion chamber and the other controlling the outlet of the supplemental chamber, means actuated by the movement of the piston for oscillating the said valves in one 90 direction, and means for oscillating the said valves in the opposite direction.

9. In explosive engines, the combination 95 with the cylinder, of an explosion chamber provided with an outlet connecting the said chamber with the cylinder and provided with an inlet for admitting the charge, two rocking valves, one adapted to cover the outlet and the other the inlet of the explosion chamber; a piston movably mounted in the 100 cylinder, means connected with the piston for rocking the said two valves in one direction, and means for moving the said valves in the opposite direction.

10. In explosive engines, the combination 110 with the cylinder, of an explosion chamber provided with an outlet connecting the said chamber with the cylinder and provided with an inlet for admitting the charge, the piston movably mounted in the cylinder, two valves 115 adapted to cover one the outlet and the other the inlet, means actuated by the movement of the piston by means of which one or both of said valves may be moved in one direction, means for moving the said valves in the opposite direction, and means for igniting the charge in the explosion chamber when both valves are in a closed position.

11. In explosive engines, the combination 120 with a cylinder, of a piston rotatably mounted therein, an explosion chamber having an outlet connecting with the cylinder for conveying the ignited charge against the rotatable piston, and provided with an inlet for admitting fluid composing the charge, a rock- 125

ing valve controlling and adapted to cover simultaneously the said inlet and outlet of the explosion chamber, independently of the pressure therein, and means for igniting the charge in the explosion chamber when the said inlet and outlet are closed.

12. In explosive engines, the combination with the cylinder provided with an outlet for burned gas, of a piston rotatably mounted in the cylinder and provided with a plurality of blades, an explosion chamber having an inlet for admitting the charge and provided with an outlet connecting with the cylinder for conveying the ignited charge against the said blades on the piston, a rocking valve, means for moving the said valve so as to open and close the inlet and the outlet of the explosion chamber, and means for igniting the charge in the explosion chamber when the outlet thereof is closed.

13. In explosive engines, the combination with the piston, of an explosion chamber provided with a discharge port having its outlet disposed so as to discharge against the piston and provided with means for admitting a charge into the explosion chamber, a rocking valve for covering and uncovering the said port independently of the pressure of the charge, means for igniting the charge when the valve is in the closed position, and means for then releasing the entire charge against the piston.

14. In explosive engines, the combination with the piston, of an explosion chamber provided with an inlet and an outlet port the outlet port being so disposed as to discharge against the piston, a rocking valve for covering and uncovering both ports and so disposed as to have the ignited charge force it to its seat, and means for igniting the charge when the valve is in a position covering both ports.

15. In explosive engines, the combination with a piston, of an explosion chamber provided with an outlet discharging against the piston, a valve controlling said outlet, a conductor for conveying fluid to the explosion chamber, a valve controlling the passage of fluid through said conductor, means for actuating both valves independently of each other and independently of the pressure in the expansion chamber, means controlled by the speed of running of the engine for regulating the action of the valve controlling the passage of fluid through the said conductor, and means for igniting the charge when the outlet valve is closed.

16. In explosive engines, the combination with a piston, of an explosion chamber provided with an inlet and having an outlet discharging against the piston, two rocking valves one controlling the outlet and the other the inlet to the explosion chamber, means for opening and closing the valve controlling the outlet, means for opening and

closing the valve controlling the inlet independently of the opening and closing of the other valve and independently of the pressure in the explosion chamber, and means for igniting the charge when both valves are in the closed position.

17. In explosive engines, the combination with the rotatable piston, of a cylinder having an outlet and having mounted therein the said rotatable piston, an explosion chamber having an inlet and having an outlet connecting with the said cylinder, an oscillatory valve controlling independently of the pressure in the explosion chamber the said outlet, means for igniting the charge in the explosion chamber when the said valve is in the closed position, and means for opening the valve after ignition and releasing the entire charge against the piston.

18. In explosive engines, the combination with the cylinder, of a combustion chamber provided with an outlet connecting said chamber with the cylinder, a rotary piston in the cylinder having blades adapted to pass consecutively opposite said outlet when the piston is rotated, a supplemental chamber having an inlet for admitting the charge therein and having an outlet connecting with the combustion chamber, two rocking valves, one controlling the outlet of the combustion chamber and the other controlling the outlet of the supplemental chamber, means actuated by the movement of the piston for rocking said valves in one direction, and means for rocking said valves in the other direction.

19. In explosive engines, the combination with the cylinder, of an explosion chamber having an outlet connecting with said cylinder and having an inlet for admitting the charge, two rocking valves, one controlling the outlet and the other the inlet of the explosion chamber, a rotary piston in the cylinder having blades adapted to pass opposite said outlet when the piston is rotated, means connected with the piston for oscillating said valves in one direction, and means for moving the valves in the opposite direction.

20. In explosive engines, the combination with the cylinder, of the piston mounted therein, an explosion chamber having an outlet connecting with the cylinder and having an inlet for admitting the charge, two rocking valves one controlling the outlet and the other the inlet of the explosion chamber, means actuated by the movement of the piston for rocking said valves in one direction, said actuating means providing that the valve controlling the outlet may be moved independently of the movement of the other valve, and means for moving the valves in the opposite direction.

21. In explosive engines, the combination with the cylinder, of the combustion chamber having an outlet connecting with the cylinder and having an inlet for admitting the

charge, of the piston rotatively mounted in the cylinder and having blades adapted, when the piston is rotated, to pass opposite said outlet, two valves one controlling the 5 outlet and the other the inlet, means actuated independently of the pressure in the combustion chamber for closing said valves independently of each other, means for igniting the charge in the combustion chamber 10 when both valves are closed, and means for opening said valves.

22. In explosive engines, the combination with a cylinder, of a combustion chamber having an outlet connecting with the cylinder, and having an inlet for the admission of the charge, a piston movable in said cylinder, 15 two valves one controlling said outlet and the other said inlet, means actuated independently of the pressure in the combustion chamber for closing said valves independently of each other, means for igniting the charge when both valves are closed, and means for opening said valves.

23. In explosive engines, the combination 25 with a cylinder, of a combustion chamber having an outlet connecting with the cylinder, and having an inlet for admitting the charge, a piston movable in said cylinder,

two valves one controlling said outlet and the other said inlet, means for igniting said 30 charge when both valves are in the closed positions, means actuated independently of the pressure in the combustion chamber and controlled by the piston for opening and closing said valves independently of each 35 other.

24. In explosive engines, the combination with a cylinder, of a combustion chamber having an outlet connecting with the cylinder and having an inlet for admitting the 40 charge, a piston rotatively mounted in the cylinder and having blades adapted to pass opposite said outlet, two valves controlling one the outlet and the other said inlet, means for igniting the charge when both valves are 45 closed, and means actuated independently of the pressure in the combustion chamber and controlled by the piston for opening and closing said valves independently of each other.

In testimony whereof I affix my signature in presence of two witnesses.

GEORGE J. WEBER.

Witnesses:

WARREN D. HOUSE,
HENRY F. ROSE.
